UNITED STATES PATENT OFFICE.

RALPH WHIPPLE, OF PARKIN, ARKANSAS.

RAFTING APPARATUS.

1,187,213.

Specification of Letters Patent. Patented June 13, 1916.

Application filed January 26, 1916. Serial No. 74,373.

To all whom it may concern:

Be it known that I, RALPH WHIPPLE, a citizen of the United States, residing at Parkin, in the county of Cross and State of Arkansas, have invented a new and useful Rafting Apparatus, of which the following is a specification.

This invention relates to apparatus especially designed for use in forming log 10 rafts.

Heretofore the construction of log rafts has been effected by connecting the logs with timbers and the like, long spikes being driven into the logs for the purpose of 15 holding the parts together. These spikes have been objectionable not only because they form holes in the logs and thus produce a considerable waste of lumber but also because if any of the spikes should be 20 left by accident within the logs, they would injure the saws used for cutting up the logs.

One of the objects of the present invention is to provide means whereby the logs can be held together without the necessity 25 of driving spikes into them, thus producing a considerable saving of lumber and at the same time avoiding the danger and injury likely to result from leaving spikes within the logs.

30 A further object is to provide log tying means which can be applied readily to the logs and which is quickly adjustable to logs of different diameters.

With the foregoing and other objects in 35 view which will appear as the description proceeds, the invention resides in the combination and arrangement of parts and in the details of construction hereinafter described and claimed, it being understood 40 that changes in the precise embodiment of the invention herein disclosed, can be made within the scope of what is claimed, without departing from the spirit of the invention.

In the accompanying drawings the preferred form of the invention has been 45 shown.

In said drawings:—Figure 1 is a plan view of a portion of a log raft having the present improvements combined therewith. 50 Fig. 2 is a section on line A—B Fig. 1. Fig. 3 is a section on line C—D Fig. 2. Fig. 4 is a horizontal section through one of the hangers of the structure and showing one form of log engaging jaw. Fig. 5 is a like 55 view showing a double jaw. Fig. 6 is a

detailed view of one of the pawls used in connection with the apparatus.

Referring to the figures by characters of reference 1 designates a bar of any suitable length and formed in one side of this bar is 60 a longitudinal series of ratchet teeth 2. Either or both ends of the bar 1 may be provided with an opening 3 for the reception of a chain or the like whereby two bars 65 may be connected.

Bar 1 is straddled by a desired number of heads 5, each head being provided at that side remote from the ratchet teeth 2 with a hinged plate 6 having an opening 7 for the reception of a tongue 8 extending 70 laterally from the head, this tongue being provided with an opening 9 designed to receive a fastening pin 10. That side of the head engaging the toothed face of the bar 1 has an extension 11 through which extends 75 an angular opening 12 and mounted on this extension is a handle 13 provided with a recess 14. Slidably mounted in the opening 12 is an angular pawl 15 having a head 16 which projects into the handle 13, there being a spring 17 housed within the handle and bearing against head 16 so as thus to hold the pawl 15 normally in engagement 80 with one of the teeth 2. All of the pawls 15 are so positioned as to slip in one direction 85 along the bar 1 but they will engage the teeth and prevent the heads 5 from being moved in the opposite direction along the bar.

Formed within the bottom of each head 90 5 is a socket 18 and secured within each socket is a bar 19. Any desired number of these bars and their heads are employed, the end bars of the series being provided with jaws, one of which has been illustrated 95 in Fig. 4. This jaw is in the form of a block 20 having an opening 21 therein through which the bar 19 extends, the jaw being fastened to the bar by means of a set screw 22. One end of the block is curved 100 upwardly and pointed as shown at 23. The intermediate bars of each series are provided with double jaws such as illustrated in detail in Fig. 5, each of these double jaws including a block 24 having an opening 25 105 through which the bar 19 extends, there being a set screw 26 for fastening the block to the bar. Each end of the block 24 is upturned and pointed as shown at 27.

In using the apparatus herein described, 110

2
a bar 19 having a jaw 20 thereon is applied to the bar 1 by swinging the plate 6 downwardly and slipping the head 5 laterally onto the bar 1, after which plate 6 is swung upwardly onto the tongue 8 and fastened by means of pin 10. Jaw 20 is adjusted upwardly or downwardly along the bar 19 until it is brought to position just below the center of the log to be engaged. Bar 1 is then placed on the log and the jaw 20 is tapped with a sledge so that the point thereof will be driven a short distance into the log. Another head 5 is placed on the bar 1 adjacent the other side of the log and is fastened to the bar 1 as hereinbefore pointed out. The said head is then drawn toward the log, the pawl 15 slipping over the ratchet teeth 2. When the head is brought against the log, the jaw is tapped with a sledge so that one of the points 27 will enter the log. A second log is then positioned under the bar 1 and against the bar 19 last put in place and will engage the other point 27 on the jaw 24. A third head 5 is then placed on the bar 1 and hanger 19 adjusted against the second log as hereinbefore described. This operation is repeated until a number of logs have been coupled by the bar 1 and the parts depending therefrom.

30 It is to be understood that any number of bars 1 can be placed upon each raft.

In the drawings, the logs of the raft have been indicated at L.

It is to be understood that the bar 1 may be made hollow, as shown in Fig. 3, thus to materially reduce the weight thereof.

In order to limit the movement of the end head on the bar 1, a stop rib 28 is formed on one side of the bar as shown particularly in Figs. 1 and 2.

40 What is claimed is:—

1. Rafting apparatus including a ratchet bar, heads adjustably mounted thereon, means carried by each head and coöperating with the ratchet bar for holding the head against movement in one direction along the bar, log spacing means connected to the heads, and log engaging jaws carried by said spacing means.

50 2. Rafting apparatus including a ratchet bar, heads slidably mounted thereon, means carried by the heads and coöperating with the ratchet bar for holding the heads against movement in one direction, bars depending from the heads, and log engaging

jaws adjustably mounted on said depending bars.

3. Rafting apparatus including a ratchet bar, a head slidably mounted thereon, means carried by the heads and coöperating with the bar for holding the heads against movement in one direction, bars depending from the heads, and pointed log engaging jaws adjustably mounted on the depending bars.

4. Rafting apparatus including a ratchet bar, a head straddling the bar and slidably mounted thereon, a retaining plate hingedly connected to the head, coöperating means upon the plate and head for holding said plate in position to secure the head upon the ratchet bar, means carried by the head and coöperating with the ratchet bar for holding the head against sliding movement in one direction along the bar, a bar depending from the head, and log engaging means carried by the depending bar.

5. Rafting apparatus including a ratchet bar, a head straddling the bar and slidably mounted thereon, a retaining plate hingedly connected to the head, coöperating means upon the plate and head for holding said plate in position to secure the head upon the ratchet bar, means carried by the head and coöperating with the ratchet bar for holding the head against sliding movement in one direction along the bar, a bar depending from the head, a block adjustably mounted on the depending bar and having a pointed log engaging end.

6. Rafting apparatus including a ratchet bar, a head slidably mounted on and straddling the bar, a plate hingedly connected to the head, means for securing said plate against movement relative to the head, said plate constituting means for preventing removal of the head from the bar, means carried by the head and coöperating with the ratchet bar for holding the head against sliding movement in one direction along the bar, a bar depending from the head, and a pointed jaw adjustably connected to the depending bar.

In testimony that I claim the foregoing as my own, I have hereto affixed my signature in the presence of two witnesses.

RALPH WHIPPLE.
